HARRY BALL, OF WORCESTER, MASSACHUSETTS, ASSIGNOR, BY MESNE ASSIGNMENTS,
TO WORCESTER SHOCK ABSORBER CO., OF WORCESTER, MASSACHUSETTS.

MECHANISM FOR AUTOMATICALLY CLOSING FIRE-DOORS.

1,257,301.

Specification of Letters Patent. Patented Feb. 26, 1918.

Application filed June 13, 1913. Serial No. 773,385.

To all whom it may concern:

Be it known that I, HARRY BALL, a citizen of the United States, residing at Worcester, in the county of Worcester and 5 Commonwealth of Massachusetts, have invented a new and useful Improvement in a Mechanism for Automatically Closing Fire-Doors, of which the following, together with the accompanying drawing, is a specification.

10 My invention relates to door closing mechanism and more particularly to devices adapted to close doors automatically in case of fire, the heat from the fire acting to release certain parts of the mechanism so as to allow it to operate.

One object of the invention is to provide 15 a simple and reliable form of automatic door closing mechanism and one which is not liable to get out of order.

Another object of the invention is to provide an automatic door closing mechanism which will set itself automatically when the door is opened, which will not interfere with the manual opening and closing 25 of the door in the usual way and which will normally hold the door in either open or closed position.

Other objects and advantages will appear 30 from the following description taken in connection with the accompanying drawing, in which Figure 1 is a plan view of a portion of an open door equipped with one form of my invention; Fig. 2 is an elevation of 35 the upper portion of the door with its closing mechanism in the position shown in Fig. 1; Fig. 3 is a plan view of the door and its closing mechanism shown in Fig. 1 after the closing mechanism has been released and 40 the door closed thereby; Fig. 4 is a view of the fusible link shown in Figs. 1 and 3; and Fig. 5 is a bottom view of a portion of a modified form of the invention.

Like reference characters refer to similar 45 parts in the different figures.

In the form of the invention shown in Figs. 1 to 4 inclusive of the drawing, the door closing mechanism is patterned largely after the usual and common form of door 50 check and includes the casing 1 mounted, as usual, at the upper end of the door 2 and a short distance from the hinged edge of the door. A horizontal arm or lever 3 is carried by the upper end of a shaft 4 pivotally 55 mounted along the vertical axis of the cas-

ing 1, the shaft 4 and the lever 3 being actuated by mechanism 4' within the casing 1. This actuating mechanism may be of any suitable construction and, as such mechanism is common and well known and as it 60 forms no part of the present invention, it is shown only diagrammatically and a description of the details thereof is not deemed necessary.

The free end of the lever 3 is pivotally 65 connected to one end of a second arm 5, the other end of this second arm being pivotally attached to the wall 6 just above the doorway. This second arm 5 is adjustable in length, as usual. The pin or catch 7 fits slidably 70 in the opening 8 formed in the downwardly extending projection 9 of the arm 3. The axis of the pin 7 is parallel with the arm 3 and, when moved toward the shaft 4, the outer end of the pin 7 is adapted to engage 75 the notch 10 in the peripheral flange 11 at the upper edge of the casing 1. The inner reduced end or shank 12 of the pin 7 is supported and guided by the small cup shaped member 13 and it also fits slidably 80 in the opening 8. A spiral spring 14 surrounds the shank 12 of the pin between the inner ends of the cup shaped member 13 and the enlarged head of the pin.

The pivot 15, extending downwardly 85 from the arm 3, supports the lever 16. When this lever is in the position shown in Figs. 1 and 2, the end of its short arm presses against the cup shaped member 13 which, in turn, causes the spring 14 to hold 90 the outer end of the pin 7 in yielding engagement with the notch 10 of the flange 11. The lever 16 is held in this operative position by a fusible or thermally operable link connected at its opposite ends to the pin 17 95 at the end of the long arm of the lever 16 and the pin 18 at the free end of the arm 3. This fusible link may be of any desired form, the form shown being composed of two members 19 and 20 joined by fusible 100 metal 21.

The force of the spring 14 is sufficient to hold the pin 7 in engagement with the notch 10 when the mechanism is arranged as shown in Figs. 1 and 2, so that the actuating mechanism in the casing 1 cannot operate and the door will remain open. When the fusible metal 21 is melted or softened by heat from a fire and the members 19 and 20 of the link are thus disconnected, the 110

tendency of the actuating mechanism within the casing 1 to rotate the arm 3 about the casing causes the pin 7 to be forced out of the notch 10, the lever 16 being now free to rotate on its pivot so as to allow the pin 7 together with the spring 14 and the cup shaped member 13 to move away from the flange 11. The end of the pin 7 which engages the notch 10 is tapered and the sides 5 of the notch converge to fit the pin so that the pin may be forced out of the notch as described. The pin 7 being now forced out of engagement with the notch 10, the arm 3 is free to be rotated by the actuating 10 mechanism within the casing 1 except for its attachment to the arm 5 or, in other words, the actuating mechanism is free to cause the door to close in the usual manner.

The form of the invention shown in Fig. 20 5 is the same as that which has been described with the exception of the lever 16 and the fusible link for holding this lever in its operative position, and the same reference characters are used to indicate the same 25 parts. In this modified form of the invention, the pin 18 supports a washer or button 22 of fusible metal, and the free end of the long arm of the lever 23 engages this fusible button so as to be held in its operative 30 position as shown in Fig. 5. The long arm of the lever 23 is long enough to reach the fusible button 22 so as to be retained in operative position thereby, but clears the pin 17 when released by the softening or 35 melting of the button.

In both forms of the invention the spring 14 is not much stronger than is necessary to maintain engagement between the pin 7 and the notch 10. Therefore, the door may be 40 closed by pressing against it slightly, the spring 14 yielding to allow the pin 7 to be forced out of engagement with the notch 10. After the door has been moved through a slight angle sufficient to remove the pin 45 17 from the notch 10, the actuating mechanism within the casing 1 will cause the door to close completely, the outer end of the pin 7 merely rubbing along the outer face of the flange 11. When the door is again 50 opened to the position shown in Figs. 1 and 2, the spring 14 again forces the pin 7 into engagement with the notch 10 so as to hold

the door in its open position. My invention, therefore, provides a simple and reliable mechanism which will close an open 55 door in case of fire and which will, at the same time, not interfere with the usual opening and closing of the door when desired.

While I have shown and described the details of one form of my invention, I do not wish to be limited to such details as it is obvious that certain changes may be made without departing from the spirit of the invention; but having described my invention, what I claim as new and desire to secure by Letters Patent is:

1. The combination with a movable door, of door actuating means operable to move said door to its closed position, said actuating means having a notch movable therewith, a slidable detent adapted to engage said notch, a spring normally maintaining said detent in engagement with said notch, to prevent the operation of said door actuating means, and a thermally controlled anchor for said spring. 70

2. The combination with a movable door, of door actuating means operable to move said door to its closed position, said actuating means having a notch movable therewith, a slidable detent adapted to engage said notch, said actuating means adapted to exert a constant force to move said detent out of said notch, a spring normally maintaining said detent in engagement with said notch, and adapted to yield when the force of the door actuating means is augmented, 85 and a thermally controlled anchor for said spring.

3. The combination with a movable door, 90 of door actuating means operable to move said door to its closed position, yielding means engaging said door actuating means to prevent the operation thereof, said yielding means adapted to be overcome when an initial closing force, independent of said 95 actuating means, is applied to said door, and a thermally controlled anchor for said yielding means.

Dated this ninth day of June 1913.

HARRY BALL.
